(57) **CLAIM**

The ornamental design for an intelligent communication terminal, as shown and described.

DESCRIPTION

FIG. 1 is a front perspective view of an intelligent communication terminal showing my new design; FIG. 2 is rear perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof;

FIG. 9 is an enlarged view of portion 9 in FIG. 1; FIG. 10 is an enlarged view of portion 10 in FIG. 1; FIG. 11 is an enlarged view of portion 11 in FIG. 2; FIG. 12 is an enlarged view of portion 12 in FIG. 5; and, FIG. 13 is an enlarged view of portion 13 in FIG. 7.

The broken lines in the figures are included for the purpose of illustrating portions of the intelligent communication terminal that form no part of the claimed design.

1 Claim, 13 Drawing Sheets
